GLOVE CONSTRUCTION

William H. Banovic, Milwaukee, Wis.

Application February 9, 1939, Serial No. 255,406

2 Claims. (Cl. 2—169)

My invention relates to improvements in gloves.

The object of my invention is to provide a new glove in which the back and palm portions are separated as to certain portions of the finger extensions by a single fourchette and also a glove wherein a single blank is used in conjunction with such a single integral fourchette as to minimize either the hand work or machine work necessary to complete the glove.

Another object of my invention is to provide a thumb construction cut in the form of a blank whereby to simplify the formation of the thumb and still give an open bellows type therefor to provide ample room for the end of the wearer's thumb.

A further object of my invention is to provide an integral fourchette for a glove, such fourchette easily die or hand cut from a single piece of leather without wastage or with a minimum of wastage.

In the drawings:

Fig. 1 is a back view of a complete glove embodying my invention, the disposition of my integral fourchette being disclosed between the fingers.

Fig. 2 is a somewhat diagrammatic view in perspective of the palm, back and fourchette portions of my glove in "pre-assembly" positions.

Fig. 3 is a plan of my single integral palm and back portion of my glove.

Fig. 4 is a plan view of my integral fourchette as it appears when cut or struck from the blank.

Fig. 5 is an elevation, palm view, of a thumb construction for my glove.

Fig. 6 is an elevation of my thumb construction in a view diametrically opposite that shown in Fig. 5.

Fig. 7 is an outside view of the little finger construction incorporated in my glove.

Fig. 8 is an outside view of the index finger construction embodying my invention.

Fig. 9 is a side elevation of one of the middle fingers of the glove construction embodying my invention.

Fig. 10 is a plan view of my blank for forming a thumb of my glove and showing the bellows fourchette for the tip thereof.

Like parts are designated by the same reference characters throughout the several views.

I attribute the success of my invention to the fact that I have not only improved the appearance and comfort of a glove but I have also provided a single fourchette which is so economical-ly derived without wastage from a small piece

of material which might otherwise be in itself waste material and which is readily assemblable with the palm and back portions of a glove by relatively unskilled labor.

While my drawings show a glove made from an integral blank for palm and back portions, my invention obviously will be as easily incorporated in a glove in which such portions are separately cut.

As shown in Fig. 3, the integral blank 20 to 10 form the palm 21 and back 22 portions of my glove is either hand or die cut to provide slots 23 and 24 to delineate front and back portions 25 and 28 of the little finger. Slots 27 and 28 to 15 to demarcate with said slots 23 and 24, the back portion 29 and the front portion 30 of the third finger. Slots 31 and 32 to demarcate with said slots 27 and 28, the back portion 33 and the front portion 34 of the middle finger and a notch 35 to indicate the end of a fold line 36 (Fig. 1) and 20 to delineate the tip of the index finger.

It will be seen from close examination of the blank thus far described that the finger portions attached to the palm 21 and to the back 22 are of identical length. I find this best suited to my invention since the continuous fourchette hereinafter to be described fits naturally to the tips of the fingers when such tips are of identical length. It will be seen, of course, that the slots 23, 27 and 32 extend more deeply into the back 30 portion 22 than do the corresponding slots 24, 28 and 31 thus providing for the inherently greater length of the human finger at the back of the hand. It is to the slanting crotch between the fingers that the peculiar and particular shape of my fourchette blank is directed.

The blank shown in Fig. 3 having been folded along a fold line indicated in a dotted line at 38, the palm and back portions 21 and 22 take their natural positions as shown in Figs. 1 and 2 40 and the integral fourchette 40 which forms such an important part in my invention is receivable between the finger portions for final assembly therewith.

My continuous integral fourchette shown 45 clearly in Figs. 2 and 4 is cut by hand or die cut to the shape shown in Fig. 4. It will be noted that there are three hairpin bends at 41, 42 and 43 to provide properly shaped crotch sections for the fourchette to be disposed at the three 50 crotches, at 44, 45 and 46, respectively, and between these crotch sections the fourchette narrows down somewhat at 47 and 48 to provide the tips of the middle and third fingers, respectively, the wider portions of the fourchette adjacent the 55

crotches 41, 42 and 43 being intended to provide for the thickened sections of the fingers of the wearer adjacent the bases of the fingers.

At the ends of the fourchette 40, I provide 5 tapered tips 49 and 50 which extend around the tips of the little finger and index finger, respectively, and terminate at the ends of the notches 35 and 51, respectively, notch 51 being formed when the seam along the line 36 is closed by 10 sewing or otherwise, thus providing a bellows type tip for each of said fingers.

As shown in Fig. 2, when my fourchette 40 is folded into the shape to take its place between the fingers of the folded blank 20, a simple sewing operation extending from tip to tip 49-50 and back again completes the assembly of the finger portions of the glove which constitutes the most difficult hand or machine work to be encountered in the assembly of any glove.

20 Any glove maker will find it exceedingly easy to assemble the finger sections and my continuous fourchette since the shape of the crotch portions 41, 42 and 43 will be found to adapt themselves, seemingly automatically, to the sloping crotch between the fingers and to dispose the intermediate sections such as 47 and 48 along the side seams of the fingers.

Likewise around the tips of the index and little fingers, the pointed sections 49 and 50 provide 30 bellows tips for these fingers and naturally close into the notches 35 and 51 without skillful fitting.

The closing of the seam at 36 is, of course, the simplest of hand or machine sewing and 35 there remains merely the provision of a thumb to complete the glove.

The blank 55 for my glove thumb is made as shown in Fig. 10 to provide a thumb and thumb tip in keeping with the type of construction 40 which is found in the index and little fingers of my glove and, in fact, in keeping with my entire glove construction. My thumb 55 is in general an orthodox, well known type of thumb construction for reception into an assembly along 45 the margins of the thumb gouge 37, but in addition thereto, I provide a bellows type fourchette completely around the tip 56 which is preferably cut integral with the blank but which, of course, may be made as a separate insertable 50 bellows tip if so desired. I have found, however, that in practical glove making the formation of the bellows tip 56 integral with the blank is the more practical and acceptable practice unless a contrasting material or color is desired.

55 The blank 55 is folded along a dotted line 57 shown in Fig. 5 and the seam upon the opposite face of the thumb at 58 is closed by sewing or otherwise, thus leaving the bellows type tip 56 to be secured to the tip margins of the thumb along 60 the lines 59 and 60, thus completing the glove.

From the above description, it will be seen that the seam lines whereby to secure by integral fourchette 40 between the finger portions as shown in Figs. 1 and 2, is the simplest of glove 65 manufacturing operations, either when viewed from the point of view of hand or machine man-

ufacture. In fact, I have found that a glove made in accordance with my invention requires no "fitting up" but is readily handled from beginning to end as an assembly operation by the ordinary "closer." In fact, a closer can initiate 5 a sewing operation either in handwork or by machine at the point 51 which starts around the tip of the little finger and can follow either the palm line or the back line of stitching throughout my fourchette to the tip 50 thereof. Then, 10 without releasing the stitch, the work may be inverted and the stitch upon the opposite palm or back face may be completed not only to the point 51, but actually throughout the seam along the line 36 to the wrist margin of the glove. 15

The thumb portion of the glove assembly is, of course, a separate stitching operation but is likewise of the simplest type and the bellows tip 56 is readily closed in without exercise of 20 special skill.

Not only is the assembly of my glove simplified, but the materials initially used for the blank 20 for my fourchette 40 and for the thumb 55 with the bellows tip 56 result in no waste material or in such insignificant waste as to be a 25 marked improvement over any type of glove manufacture heretofore provided.

To those skilled in this art, it will be apparent likewise that my invention is adapted not only to leather but to any other types of material acceptable for glove construction and that where contrasting materials either as to color or quality are to be worked into a single glove, the resultant product will be found to have style and a degree of conservative taste due to the fact 30 that my fourchette has eliminated seams or joints at the finger tips and crotches. It is, therefore, not excessively conspicuous and is readily adapted to either gauge, P.K., inseam, trimmer or hand construction, and it will be found that in gloves 40 requiring special strength quirks may be incorporated without complication. Furthermore, dies customarily heretofore used for palm and back portions are usable without change in making my improved glove. 45

I claim:

1. A thumb for a glove, said thumb including a blank folded medially and provided with a notch and curved ends adjacent the thumb tip, the tip of the thumb having a fourchette extending integrally with said blank from the notch, and a line of stitching securing the fourchette to the curved ends and connecting the free margin of the thumb to close the same opposite the folded line. 55

2. A fourchette for a glove comprising an integral strip of fourchette material of a length to extend from the index to the little finger tips and having three acute angles, one of said angles being approximately midway of the length of 60 the fourchette and the other two being spaced from the respective ends thereof a distance slightly greater than the length of the index and little fingers respectively of the glove to be formed thereby. 65

WILLIAM H. BANOVIC.
